SUSPENSION JACK

Filed Oct. 7, 1929

Fig. 3.

Inventor.
Harry Van Dyken

By *Wilson & Lambert* Attys

UNITED STATES PATENT OFFICE

HARRY VAN DYKEN, OF TWO HARBORS, MINNESOTA

SUSPENSION JACK

Application filed October 7, 1929. Serial No. 393,062.

My invention relates to jacks and more especially to suspension jacks in which the operating parts are below the level of the supporting member.

5 In the assembling and repairing of heavy vehicles such as railway locomotives and the like, it is often necessary to remove and replace heavy members from the lower parts of the machine, and the limited space provided is usually insufficient for ordinary types of levers or jacks to assist in these operations. While such work is often done while the machine or engine is over a pit or floor opening, only aggravates rather than eases the situation. My present invention has been devised and improved to overcome the difficulties met under these circumstances and to provide a jack of the suspension type which can be used in connection with a pit or floor opening, and in which the operating parts are below the suspension members, and providing for lifting of heavy objects from a substantially flat surface.

It is an object of my invention to provide 25 a jack adapted for the lifting of objects from a plane surface.

Another object of my invention is to provide a jack wherein the operating parts are below the level of the supporting members.

30 Another object of my invention is to provide a jack adapted to be used in connection with a pit or floor opening.

Further objects and advantages will appear and be brought out more fully in the 35 following specification, reference being had to the accompanying drawings in which—

Figure 1 is a side view of a jack embodying my invention;

Figure 2 is an end view of the same; and 40 Figure 3 is a sectional view taken along the lines 3—3 of Figure 1.

Referring more particularly to the drawings I show a jack comprising a body portion 10, having side plates 11 which are secured together in spaced relation by a number of space bolts 12 and 13. At the top of side plates 11 are bearing plates 14, which are shown as angle iron members and made integral with sides 11 or suitably secured thereto as by bolts 15. Bearing plates 14 provid-

ing outwardly projecting portions, make possible the suspension of the jack in an aperture 16, in a pit plank 17, which plank may be suspended across a pit or other floor opening suitable for the desired use. An elevating member 18 is disposed between plates 11 and, as may be seen from Figure 3, is shown as a hollow member and is provided with a rack 19 disposed along one side and integrally secured thereto. A top plate 20 is secured to the top of elevating member 18, and has an extended portion 21 for insertion into the hollow portion of member 18, and is secured in place by lock bolt 22. The pinion 23 mounted on a shaft 24 is suitably secured between plates 11, and is fixed to shaft 24 and adapted to rotate with it. Pinion 23 is so mounted as to engage the teeth of rack 19, so that the rotation of pinion 23 will raise or lower rack 19 and with it top plate 20, and elevating member 18. Shaft 24 is provided with a squared portion 25, to which an operating crank or lever may be attached as desired. A dog 26 is mounted on a shaft 27, and arranged to engage rack 19 and hold the elevating member in any desired position. An arm 28 is secured to shaft 27, and has a knob or handle 29 at its outer end. Bolts 30 are each provided with a guide roller 30 adapted to guide the elevating member 18 and reduce the friction of its movement.

In operation the pit plank 17 is placed across the pit and with the jack suspended in the aperture 16 by the supporting members 14. With the elevating member 18 in its lowest position, top plate 20 will rest on bearing plate 14, and the locomotive binder or other parts to be elevated placed on top plate 20. Shaft 24 can then be rotated and, with the cooperation of dog 26, elevating member 18 can be raised to and held at any position, as will be clear to anyone familiar with this type of device. To lower the object, member 18 must be first elevated slightly by operation of shaft 24, and the dog 26 released from rack 19 after which the member 18 can be lowered by the weight of it and its superimposed load.

From the foregoing it will be apparent that this jack is adapted for all purposes in which

it is desired to lift an object from a plane surface such as a floor, which has a pit or other opening, across which a plank supporting the jack can be placed. The body of the jack and the operating parts are all below the supporting members, and with sufficient space provided below the supporting members 14, the jack can be easily and readily operated as illustrated.

Having described my invention it will be understood that changes and modifications in the design and construction of the illustrated device may be made without departing from the true scope of the invention as set forth in the appended claims.

I claim:

1. A jack comprising, in combination, body members, supporting members secured thereto, an elevating member, and actuating means therefor, said supporting members being located adjacent the top of said body.
2. A jack comprising, in combination, a body portion having separated side members, supporting members connected to said side members adjacent the upper portion thereof, an elevating member disposed between said side members, and actuating means for said elevating member engaging said side members and said elevating member.
3. A jack comprising, in combination, spaced supporting members, a body portion secured to and supported by said supporting members and disposed therebelow, an elevating member in said body portion, means for actuating and locking said elevating member, and a plurality of roller guides for said elevating member.
4. A jack comprising, in combination, a plurality of spaced supporting members, a body portion secured thereto and disposed therebelow, said body portion having separated side members, an elevating member having a rack in said body portion, actuating and locking means engageable with said rack, and guide members for said elevating member.
5. A jack comprising, in combination, a plurality of spaced supporting members having a substantially flat upper portion and a downwardly extending portion, a body portion secured to said downwardly extending portions of the supporting members, an elongated elevating member disposed within said body portion, a rack extending along and secured to said elevating member, a top plate secured to the top of said elevating member, means for actuating and locking said elevating members, and means for guiding said elevating member.
6. A jack comprising, in combination, supporting members having a substantially flat supporting portion and a downwardly extending portion, a body portion having spaced side members secured to the downwardly extending portions of said supporting

members, said side members extending below said supporting members, an elevating member disposed between said side members, guide bearings therefor, a rack extending along and secured to said elevating member, actuating means for said rack and elevating member comprising a pinion carried by said side members, locking means comprising a dog adapted to engage said rack, an operating handle for said dog, and a top plate secured to said elevating member, said top plate being adapted to lie substantially in the plane of said supporting members when the elevating member is in its retracted position.

Signed at Two Harbors, Minnesota, this 26th day of September, 1929.

HARRY VAN DYKEN.
